UNITED STATES PATENT OFFICE

MAURICE ALLAND, OF ATLANTIC CITY, NEW JERSEY

TOP

Application filed October 11, 1928. Serial No. 311,831.

The object of the invention is to provide improvements in spinning tops, and particularly in those which are used for the playing of games. Such games may be of any character for which the construction of the top is suitable and may be given any desired names depending upon the rules governing and the method of playing the particular games in mind. However, purely for the purpose of illustration, and without in any degree limiting the scope of the invention, the two forms of tops herein disclosed will be referred to as dice and roulette tops, since among numerous games of entertainment which may be played with the present devices, the tops are adapted for use in playing those games which are sometimes played with roulette wheels and dice.

An object has been to provide a so-called roulette top with a cavity containing one or more of movable elements and having circumferentially positioned peripheral recesses, with means to manually set the top in motion, and a relatively pointed extension upon which the top is adapted to spin as long as its inertia of rotation is sufficiently maintained, after which the top is adapted to fall upon one side and the elements move by gravity into a corresponding number of said recesses, the floor of the said cavity being preferably concave, so as to maintain the movable elements centrally positioned while the top is spinning.

Another object has been to provide a modified form of so-called dice top having a cavity containing one or more movable elements and having circumferentially positioned recesses, with means to manually set the top spinning, and a flattened or substantially cylindrical extension upon which the top is adapted to rest in upright position while not in motion, but which extension partly counterbalanced by said spinning means operates to prevent the top from spinning in an upright position as does the roulette top, but instead causes the top to spin upon a portion of its outer periphery, until its inertia of rotation dies down and the top falls again upon said flattened extension, at which time the said elements roll into a corresponding number of

said recesses, due to the floor of said cavity being convex.

With these general objects and principles of construction in mind, the invention comprises further details of construction and operation such as are fully brought out in the following description, when read in conjunction with the accompanying drawings, in which Fig. 1 is a top plan view of the so-called roulette top, a portion of which is broken away to show the shape of the interior; Fig. 2 is a central vertical section of the same in the position assumed while spinning; Fig. 3 is a top plan view of the so-called dice top, a portion of which is broken away to show the shape of the interior; Fig. 4 is a central vertical section of the same in the position assumed while at rest; and Fig. 5 is an elevational view showing the position of the top while spinning.

Referring to Figs. 1 and 2 of the drawings, a hollow member is shown as comprising a substantially cylindrical wall 1, having inwardly directed circumferentially positioned recesses 2, preferably cylindrical in shape, the lower end portion of said wall being spanned by a bottom wall 3, having a depending relatively pointed projection 4 and an upwardly positioned concave inner surface 5, upon which rest any desired number of balls or other form of movable elements 6.

The upper peripheral portion of the wall 1 terminates in a restricted cylindrical flange 7, adapted to receive the peripheral portion of a transparent closure member 8, which is secured to said hollow member by spinning or otherwise inwardly deflecting the free edge portion 7' of said flange. Extending upwardly from the central portion of the closure 8 is an integral projection 9, adapted to be manually engaged for the purpose of imparting to the top a spinning motion.

The upper surface of the wall 1 at one point is provided with any suitable means such as a pin 10 which extends into a recess 11 in the closure 8 and operates to positively prevent relative movement between said hollow member and its closure. The result of this construction is that when the manually engageable projection 9 is rapidly rotated, a

similar rotary motion is imparted to the other portions of the top and as long as sufficient rotary inertia is maintained, the top will spin upon the pointed projection 4 in the position shown in Fig. 2, and due to the concave nature of the surface 5, the balls or similar movable elements 6 remain in the center of the top.

However, when the inertia of rotation decreases below a critical point, the top tilts and falls toward one side until it rests not only upon the projection 4, but also upon a portion of the peripheral edge 12, at which time the movable elements 6 roll into a corresponding number of recesses 2. The recesses entered by said elements are not necessarily adjacent, as said elements enter said recesses while the top continues to roll slightly upon the edge 12. Also, it will be noted that the upper surface of the wall 1 is provided with any desired set of numerals, letters, or other symbols to indicate points won or lost in playing a given game, the symbols being read as they may correspond with the positions of the respective elements 6 after coming to rest upon the cessation in the rotation of the top.

Referring to Figs. 3, 4 and 5, a second form of top is illustrated as comprising a hollow portion having a preferably cylindrical wall 15, provided with circumferentially positioned preferably semi-cylindrical recesses 16 in its inner face, the lower edge portion 17 of said wall being spanned by a bottom wall 18, the upper surface 19 of which is convex, while the lower surface is provided with a unitary projection 20 having a flattened base surface 21.

The upper free end of the wall 15 is restricted to form a slender cylindrical flange 22, adapted to receive and to be mechanically spun or turned over the radially outer free edge portion of a preferably transparent closure 23, from the center of which closure rises an axial extension 24, which is adapted to be manually gripped for the purpose of setting the top in motion. The upper portion of the wall 15 at one point is provided with a pin or lug 25, which extends into a recess 26 in said closure and thereby forms a positive means for preventing the relative rotation of the hollow portion and its closure.

Within the top there are positioned any desired number of movable elements such as the balls 27 and these, when the top is at rest in upright position as shown in Fig. 4, gravitate radially outwardly into a corresponding number of the recesses 16. When the top is spun by means of the extension 24, since it does not have a pointed extension such as that of the top shown in Fig. 2, it tends to turn upon one side of the cylindrical wall 15 and spins, in a position approaching that shown in Fig. 5, no doubt due partly to the fact that the weight of the extension 24 par-

tially counterbalances the weight of the projection 20.

However, as soon as the spinning inertia decreases below the critical point, the excess weight of the projection 20 causes the top to fall again into the position shown in Fig. 4, but in so doing it staggers about in such manner as to thoroughly agitate or shuffle the movable members 27 with the result that they are still in motion when the top ceases to move, and immediately after which they gravitate into a corresponding number of the recesses 16. As the upper surface of the wall 15 is provided with numerals, letters, or other symbols adjacent to the respective recesses, the positions assumed by the elements 27, after the top has fully come to rest, indicate symbols by which the particular game is played, such for instance as points to be moved, or scores to be allowed to the respective players, it being understood in each instance that the balls 6 and 27 can be of different colors or other identifying characteristics if so desired.

Having thus described my invention, what I claim and desire to protect by Letters Patent of the United States is:—

A top, comprising a cylindrical wall having spaced recesses and spanned by a bottom wall having a depending flattened projection and a convex inner surface, a transparent closure for the upper open portion of said top provided with an extension for manually setting the top in motion, means carried by said first-named wall and engaging said closure to prevent relative rotation therebetween, and a gravity actuated element upon said convex surface adapted to roll radially into one of said recesses when the top rests upon said flattened projection.

In testimony whereof I have affixed my signature.

MAURICE ALLAND.
